UNITED STATES PATENT OFFICE.

WILLIAM M. BRUCE, JR., OF SPRINGFIELD, OHIO.

ELECTRIC-TRANSLATING DEVICE.

Application filed April 6, 1923. Serial No. 630,294.

My invention relates to improvements in methods and means for operating translating devices, such as relays or repeaters.

The principal object of the invention is to provide a method and means for operating repeaters or relays in use with radio or submarine cable reception where it is desired to operate recording or repeating devices from a small amount of received current. It is quite adapted, however, to the operation of various other forms of electrical apparatus.

In operating devices of this character by the means and methods at present employed it has been found quite possible to secure receiving devices of the vibrating coil or similar types which will respond to received current impulses, of a feeble or delicate character, but where these receiving devices are employed to operate movable contacts to pass the current necessary to operate other repeaters or other translating devices in a local circuit from a source of current supply sufficient to operate said translating device, serious difficulty is found in securing the proper contact to pass a sufficient amount of current to operate such other devices, particularly when rapid operation is desired. If current in sufficient large quantities to operate the relay or other controlling device is passed through the contacts, sparking or sticking will result or in rapid operation the contact fails with the resulting failure in the operation of the relay or other operating device.

In my improved method I make use of the well known principle that a change of potential in the grid circuit of a vacuum tube will change the flow of current in the plate circuit and I accomplish this by employing the receiving device for making and breaking a local circuit including the grid of a vacuum tube with only sufficient current supply to change the potential on the grid and operate the relays or repeaters or other apparatus by current from a suitable source of supply through the plate circuit of the tube.

By this arrangement the current passing through the contacts operated by the receiv-

ing device is practically wattless, being measured in micro-amperes, while the flow of current through the repeater or other device controlled by the potential of the tube is in a closed circuit without contacts and consequently without the possibility of 55 sparking, sticking or other troubles which would result from the use of make and break devices in a circuit having sufficient flow of current to operate said translating devices. 60

In the accompanying drawings:

Fig. 1 is a diagrammatic view showing the circuits and apparatus employed in receiving and translating current impulses from any suitable source of supply and in 65 which a vibrating coil is used for changing the potential of the tube.

Fig. 2 is a similar diagrammatic view showing the circuits and apparatus employed when used as a repeater for submarine cable and similar circuits. 70

Fig. 3 is a view of a different form of receiver:

In the said drawings *a* represents a receiving device which may be of any suitable 75 form, but which in the present drawing is illustrated as a movable coil device and which is connected to any suitable receiving circuit such as radio, telegraph, submarine cable, etc. *b* is a vacuum tube of the three-element type and *c* is a relay or other translating device which is to be operated in response to current impulses impressed on the receiver *a*.

*a*¹ is a movable part or tongue on the 85 receiver *a* adapted by the current impulses received on the receiver *a* to move against a stationary contact *a*² which is connected by wire 1 to battery *d*, wire 2 to the grid *b*¹ of the vacuum tube *b* and thence from the filament *b*² of said tube by wire 3 to the tongue *a*¹. The battery *d* may be of very small 90 capacity in a circuit supplied with suitable resistance so that the current flow through the contact will be reduced to the minimum, it being necessary only to pass the potential of the battery onto the grid *b*¹. The circuit 95 for operating the relay or other translating device *c* is from the plate *b*³ of the tube through wire 4, battery *d*¹, wire 5, relay *c*, 100

wire 6 and wire 3 to the filament. The usual circuit for illuminating the filament from the battery d^2 is supplied.

This in its simplest form describes the circuit for translating the impulses impressed upon the receiver a by the relay c or other translating device. Inasmuch as it is necessary only to transmit potential to the grid b^1 , the current passing through contacts a^1 and a^2 which may be measured in micro-amperes will permit the receiver to make the necessary contact to change the potential on the grid b^1 sufficiently to control the flow of current to the relay c without sticking or 10 sparking and at a high rate of speed while the current supplied to the relay c or other device passing through a closed plate circuit of the tube has no contacting device in which 15 sparking or sticking may occur.

20 In some cases I have found that the operation may be improved by employing a shunt 7 around the contacts a^1 and a^2 provided with resistance 8 and capacity preferably in the form of a condenser 9 so that 25 charging and discharging of the condenser will assist in the change of potential on the grid in a well known manner.

In the circuit which I have described for the relay c positive current would flow from 30 the plate to the filament whenever the filament is illuminated which would have a tendency to cause the relay or other device c to become magnetized and close the contacts at all times by this flow of current.

35 This may be obviated by spring tension on the armature which would prevent its being operated except when the flow of current is increased by the change of potential on the grid. I have shown, however, a method of 40 overcoming this which I have found effective and desirable in certain cases and which consists of a battery d^3 in a line between the filament and grid and having resistance 10 so proportioned as to give the grid a sufficient negative potential to prevent the flow 45 of current from the battery d^1 thus producing a zero current through the relay c except at such times as the potential of the grid b^1 is changed.

50 In Fig. 2 I have shown in diagram a circuit particularly adapted for repeating impulses from submarine cables. In this case the circuit is duplicated, a second contact aa^2 is provided on the opposite side of the 55 movable contact a^1 which, in turn is connected to the grid bb^1 of a second tube bb and a second repeating relay or other device cc is employed in circuit with the plate circuit of said tube bb so that as the tongue 60 a' is moved in one direction it will control the potential on the grid circuit of the tube b by contact a^2 and when moved in the other direction it will control the potential on the tube bb by the contact aa^2 . As the movable 65 coil or receiving apparatus moves in one

direction in response to a negative impulse corresponding to one code signal, one of the translating devices will be operated and when moved in the opposite direction in response to a positive impulse, the other relay will be operated and these current impulses representing dots and dashes of cable code would be relayed or repeated as desired.

70 It will be understood that any suitable form of receiver may be employed that will respond to the received current impulses. For wireless reception I preferably employ a vibrating receiving device which, if desired, may be mechanically tuned to certain frequencies as set forth in my pending application Ser. No. 445,968. So long as the vibrations of the receiver continue, the contact at a^2 will be maintained sufficiently to control the potential on the grid b^1 and cause the relay or other device c to be held 75 in its advanced position and when these vibrations cease, the relay will drop back and thus provide means for repeating the impulses. One of the forms of receiving devices which has been successfully employed with this method and with these circuits is shown in Fig. 3 in which a vibrating reed e operated from a coil e^1 and having a movable contact e^2 to engage the stationary contact e^3 through which the 80 circuit through the tube is maintained.

90 Inasmuch as the flow of current to the controlling device is controlled by a change of potential which is secured by making and breaking the grid circuit having a practically wattless current, a very high magnification of the current to the relay from that passing through the contacts is secured and inasmuch as the relay or controlling device is operated in a closed circuit without contacts the positive operation of the controlling device is secured at all times and 95 at high speeds.

Having thus described my invention, I 100 claim:

1. In a thermionic repeater, vacuum tubes, a receiver adapted to move in one direction in response to impulses of one polarity and in the opposite direction in response to impulses of opposite polarity, contacting devices operated by the movement of said receiver in either direction, each of said contacting devices being in circuit with the grid of a vacuum tube, and separate controlling devices in the plate circuits of 115 said vacuum tubes whereby a current impulse of one polarity will be repeated by one of said controlling devices when the receiver moves in one direction and a current impulse of opposite polarity will be translated by the other translating device when the receiver is moved in the opposite direction, each of said translating devices being controlled by change of potential in the 120 grids of the respective tubes.

2. In an electric circuit system, a sensitive primary circuit relay having double contacts, a push-pull thermionic vacuum tube amplifier having the respective grids of the amplifier tubes connected to the relay contacts, a source of potential connected between the armature of the primary circuit relay and one side of the filaments of the tubes, and a local translator controlled by the plate circuits of the said amplifier. ¹⁰ In testimony whereof, I have hereunto set my hand this 31st day of March, 1923.

WILLIAM M. BRUCE, JR.
